Geo. P. Kimmel.

ATTORNEY.

UNITED STATES PATENT OFFICE.

THEODORE A. BAILEY, OF ORLANDO, FLORIDA.

DENTAL FLOSS HOLDER.

1,415,765.

Specification of Letters Patent.

Patented May 9, 1922.

Application filed July 28, 1921. Serial No. 488,112.

To all whom it may concern:

Be it known that I, THEODORE A. BAILEY, a citizen of the United States, residing at Orlando, in the county of Orange and State 5 of Florida, have invented certain new and useful Improvements in a Dental Floss Holder, of which the following is a specification.

This invention relates to dental appliances, 10 and more particularly to dental floss holders.

The object of the invention is to provide a simple and efficient implement for holding a piece of dental floss taut during its reciprocation between the teeth for cleaning, 15 medicating or other purposes.

Another object is to provide an implement of this character composed of a single piece of spring wire bent to the designed configuration, and including spaced thread receiving jaws, equipped with clamps for holding 20 the floss.

With these and other objects in view, the invention consists in certain novel features of construction as hereinafter shown, described and claimed.

In the accompanying drawings:

Figure 1 represents a side elevation of the implement constituting this invention with a piece of floss shown in operative position 30 therein, the dotted line position showing the position the parts assume when the floss is rendered taut by grasping the handle member of the implement; and

Fig. 2 is a plan or end view thereof.

In the embodiment illustrated the implement 1 constituting this invention is composed of a single piece of spring wire, bent intermediate its ends to form a loop 2, which constitutes the hand grip, or handle of the 40 implement, said loop being here shown ovate in form with the smaller end arranged at the front, and the wire extended substantially at right angles from said end in parallel relation, as shown at 3 and 4, the wire 4 being 45 twisted around the wire 3, as shown at 5, said twisted portion forming a guide loop through which the wire 3 loosely passes. After the 50 twist 5 is formed in the wire 4, said wire is extended laterally at right angles and the terminal thereof folded inwardly in close contact with the body portion, forming a jaw 6, having a floss clamping element 7.

The wire 3, below the guide 5, has a slight forward offset 8 to form a stop for limiting

the outward movement of the eye 5 on the 55 wire 3. In advance of the offset 8, the wire is extended and curved, as shown at 9, and then extended forwardly in a plane substantially parallel with the jaw 6, forming a jaw 10 for cooperation with the jaw 6, said jaw 60 10 having its end bent inwardly in contact therewith to form a clamp 11 for securing one end of the floss, shown at F.

In the use of this implement, the piece of floss F is cut the desired length and the ends 65 thereof are inserted in the clamps 7 and 11 and securely held thereby. When the loop shaped member 2 is grasped by the hand of the user and the sides thereof pressed toward each other, the eye 5 will slide upwardly on 70 the wire 3, thereby moving the jaw 6 away from the jaw 10, and stretching the floss F, securing it in taut relation between the jaws so that it may be easily inserted and reciprocated between the teeth.

From the above description, it will be obvious, that the implement constructed as herein shown and described may be very cheaply manufactured and may be nickel plated, or finished in any desired manner, 80 and yet will be very useful, especially when medicated floss is to be used between the teeth.

The preferred embodiment of the invention is disclosed in the drawings and set forth 85 in the specification, but it will be understood that any modifications within the scope of the claimed invention may be made in the construction without departing from the principle of the invention or sacrificing any 90 of its advantages.

What I claim is:

An implement of the class described composed of a single piece of spring wire bent intermediate its ends to form a substantially 95 ovate loop, wire arms extending from the smaller end of said loop in parallel relation and substantially at right angles to the loop, one of said arms being twisted around the other to form a guide therefor and then extended laterally in a plane at right angles to the arm around which it is twisted, the upper arm being extended laterally, the terminals of said arms bent inwardly to form thread clamping elements.

In testimony whereof I affix my signature hereto.

THEODORE A. BAILEY.
